corporation

Application September 1, 1933, Serial No. 687,883
In Germany May 23, 1933

11 Claims. (Cl. 125—11)

This invention relates to a device for dressing profiled grinding wheels by means of two dressing tools controlled by a former, each of the said dressing tools operating on a respective half of

5 the profile of the grinding wheel.

Means have previously been employed to dress profiled grinding wheels by a copying process in which a diamond controlled by means of a link parallelogram is employed. A dressing device 10 has also already been employed comprising two slides mounted on a rotary axle, which are connected through a lever system with one another. The one slide carries the dressing tool and the other a tracer which is guided over a former. 15 The first mentioned devices can only be constructed in grinding machines in a complicated manner and require a comparatively large space. In the last mentioned device only a shaped diamond can be used, which operates with at least 20 two corners and the intermediate edge of its profile. Apart from the fact that a shaped diamond is costly and less durable in use than a rough diamond, there are also difficulties in keeping the tracer always exactly in accord with the cutting edges of the dressing tool subjected to the wear.

25 The device according to the invention does not show these disadvantages. Its principal features are as follows:

Two dressing tools are secured side by side a 30 predetermined distance apart on a two-armed lever, which dressing tools can be normal shaped diamonds or grinding tools of very hard material. This double lever is movable about a rotary axis, which lies in a plane parallel to the 35 axis of the grinding wheel, as well as about an axis perpendicular to the plane of the grinding wheel profile, and these movements are effected from the tracer guided over a former or pattern, the tracing arm turning its guide member together with the double lever connected therewith 40 and the dressing tools and at the same time operating over suitable intermediate members, for instance a toothed rack and toothed wheel, a cam, which so operates on the double lever, that the dressing tools move in a radial direction to 45 and from the grinding wheel. The double lever carrying the dressing tools is arranged, with the cam which controls its movement to and from the grinding wheel, in a rotary shaft of the guide member of the tracing arm. In order, after the 50 completion of one profile-half to bring the one dressing tool out of engagement with the grinding wheel and the other into operative position, the double lever is movable in the direction of its 55 rotary axis.

The two positions of the lever are limited by means of stops, of which at least one is adjustable. A spring-pressed pin presses the double lever against the operative stop. The rotary shaft, on which the double lever is mounted, projects from its bearing and is provided with two oblique surfaces, which abut in each end-position of the tracer at the base of the former against stationary stops and move the shaft with the lever and dressing tools axially in one or other 10 direction. In this way when the dressing of the one profile-half has been completed, one dressing tool is automatically brought into and the other out of the operative position. The carrier for the dressing tools is movably arranged 15 on the lever and in such a manner that the cutting edge of a dressing tool can be adjusted to a position over the centre line of the profile to be produced. The whole device is arranged in a slide, which is adjustable in suitable guides with 20 respect to the grinding wheel, for location of the dressing tools and in order to allow for the decreasing diameter of the grinding wheel.

An embodiment of the invention is illustrated 25 in the accompanying drawings, in which

Figure 1 is a view in longitudinal section of the said embodiment,

Figure 2 is a plan view,

Figure 3 is a transverse section on the line 30 I—I of Figure 1,

Figure 4 is a transverse section on the line II—II of Figure 3,

Figures 5 to 7 show the dressing tools in various operative positions, the arrangement here shown being that for dressing a grinding wheel 35 for the production of Whitworth threads.

Figure 8 shows the cam path of the guide cam for the tool lever.

Figure 9 is a plan view, partly in section, of the complete device, its mounting and hood. 40

Figure 10 is an elevation, partly in section, from the right side of Figure 9, the view being turned to erect position.

Referring now to the drawings, the dressing tools 1 and 2 are secured side by side in a tool 45 holder 3 mounted on one end of a two-armed lever 4. The lever 4 is mounted on a shaft 5 and can rotate about the axis x—x. The rotary shaft 5 is mounted in the bearings 6 and 7 in a rotary hollow stub shaft 8' extending from the member 8. The axis y—y of the rotary shaft 8' is perpendicular to the plane of the profile of the grinding wheel S. It need not, as shown in the drawings, pass through the axis of rotation x—x, but can pass outside this. The member 8 serves 50

55

as a guide member for the tracing arm 9, which carries the tracing roller 11 guided over the former or pattern 10. The former 10 is secured on a slide 12, which is provided with a bearing for the rotary shaft 8'. The tracing arm 9 has a toothed rack 9', which engages with a toothed wheel 13. With the toothed wheel 13 is connected a cam 14, which rotates with the toothed wheel on a shaft 15 arranged in the rotary shaft 8'. The lever 4 carries a lug 4' which is pressed continuously by a spring 16 against the cam 14. For effecting the rotation of the cam a steel band, rope or the like under tension, can also be secured to the tracing arm 9, so as to wind on or off a drum connected with the cam and so rotate the latter.

The distance measured from the point of contact of the tracer 11 with the former 10 to the axis $y-y$ of the rotary shaft 8' bears a predetermined relation to the distance measured from the point of contact of the dressing tool 1 or 2 with the grinding wheel S to the axis $y-y$ of the rotary shaft 8'. The throw of the cam 14, taking into account the proportion of the lever arms of the lever 4 to one another, is properly proportioned with respect to the length of the profile of the former 10.

If now the tracer 11 is guided along the former, then the tracing arm 9, through the rack 9', the toothed wheel 13 and the cam 14, causes a movement of the lever 4, due to which that dressing tool situated in the operative position moves in a radial direction to or from the grinding wheel. At the same time, however, through the tracing arm 9, the guide member 8 and shaft 8', together with the lever 4 and the dressing tools is rotated around the axis $y-y$, so that the dressing tool executes, corresponding to the profile angle of the former 10, a movement in the direction of the axis of the grinding wheel. In this way there is produced on the grinding wheel a profile, which corresponds exactly with the former in a proportion corresponding to the transmission ratio of the elements transmitting the movements.

The shape of the cam 14 is shown in Figure 8. The cam path begins at the point *a* and continues to the point *b*. The greatest elevation of the cam path corresponds, in the proportion of the transmission ratio to the height of the profile of the largest former for the largest grinding wheel profile to be produced by means of the dressing device. The cam can, therefore, also be used for all smaller grinding wheel profiles. The rack 9' then moves the cam, corresponding to the lower profile-height of the former, only through a fraction of the path *a-b*.

As already mentioned, only one dressing tool is in operative position at any time during the dressing process and shapes one half of the profile, while the other dressing tool is out of engagement with the grinding wheel. For this the two dressing tools 1 and 2 are arranged a distance *A* apart in the support 3. The space *A* is somewhat larger than the actual profile-base or breadth of the grinding wheel. The dressing tools are so adjusted in the support 3 that their operative cutting-edges are the same distance from the axis $x-x$ as is indicated by means of the dot-dash line *l-l*. As shown by way of example in Figs. 5 and 6 the dressing of the right-hand half of the profile of the grinding wheel S is first effected by the dressing tool 1. After the right-hand half of the profile is dressed the dressing tool 1 must be moved out of engagement with the grinding wheel and the dressing tool 2 be moved into operative position, as shown in Fig. 7. This is auto-

matically effected since, as soon as the tracer 11 is guided over the respective end-position at the base of the profile of the former, an extension 5', projecting out of the bearing 6 of the shaft 5, engages with one or other of stop-surfaces 17 and 18 formed on said extension 5', in consequence of the rotary movement of the shaft 8' against one or other of stops 19 and 20 and thereby causes the shaft 5 to be shifted axially with the lever 4 and the dressing tools. The stops 19 and 20 are secured to the part 12' of the slide 12. When the surface 17 strikes against the stop 19 the lever 4 is moved with the shaft 5 into contact with the adjustable stop 21. Upon rotation of the shaft 8' in the other direction, the stop-surface 18 strikes against the stop 20, and the shaft 5 with the lever 4 is moved to engage the stationary stop surface 22. The dressing tools 1 and 2 are always thus shifted by the amount *A*. In order that the lever 4 shall always be exactly in contact with the stops it is provided with recesses 23, 24, into which a pin 25 snaps under the action of a spring 26. The carrier 3 for the dressing tools 1 and 2 is arranged movably on the lever 4 and in such a manner that the cutting-edges of each dressing tool can be adjusted exactly to a position over the centre line of the profile to be produced. For the adjustment of the carrier 3 two screw bolts 30 and 31 are used which are secured to the lever 4 in a suitable manner.

The slide 12, which serves for the reception of the whole dressing device and the former, is movable in suitable guides in the particularly rigidly constructed protecting cover 27 for the grinding wheel S. It can, by means of the screw-spindle 28 which co-operates with a nut 29, be adjusted with respect to the grinding wheel. The screw spindle 28 can thereby be so connected with the screw spindle for the adjustment of the grinding wheel support that the grinding wheel is automatically re-adjusted with respect to the work by the amount of the dressing, so that after the dressing of the grinding wheel the latter can be operated again without measurement being required.

Arranged in the upper part of the grinding wheel support 27' is the adjusting spindle 36 for adjusting the grinding wheel support and the dressing device. Mounted upon the adjusting spindle 36 is a worm 37 engaging a worm wheel 38. The worm wheel shaft 39 is journaled in the grinding wheel support 27' and carries at its lower end a toothed pinion 40 engaging a rack 41 fixed to the stationary base 41' of the machine. Mounted upon the rear end of the adjusting spindle 36 is a gear 42 driving a gear 44 by means of an idler gear 43. The gear 44 is mounted upon the adjusting screw spindle 28 for the dressing device. Gear 44 drives the adjusting spindle 28 by means of a friction clutch 45. The clutch member 45' is longitudinally displaceable along the spindle 28 by means of a wedge 46. The adjusting nut 47, upon being tightened, presses the hand wheel 48 upon the clutch member 45', thereby clutching the gear 44 to the adjusting spindle 28. The transmission of motion from the adjusting spindle 36 may also be effected by means of a chain drive or the like.

The grinding wheel support 27' is movably arranged in suitable guideways of the machine bed for radial movement with respect to the grinding wheel. Mounted in suitable guideways on the element 27, which is constructed as a

protecting cover or hood, is the dressing device. When dressing of the grinding wheel S becomes necessary, the grinding wheel S is moved out of engagement with the work piece W whereupon the hand wheel 49 is turned to an extent indicated upon the scale 49' by the pointer 50. In this way, an adjustment of the grinding wheel support 27 toward the work piece is effected by means of the worm gear 37, 38, and the toothed 10 gearing and rack and pinion 40, 41.

At the same time the dressing device is advanced in its guideways (by means of the gears 42, 43, 44) toward the grinding wheel S for the same extent. In other words, the grinding wheel 15 is automatically adjusted with respect to the work piece for wear caused through the grinding and for the extent desired for dressing. Therefore, after the dressing has taken place no further correction is necessary in the radial 20 adjustment of the effective grinding wheel profile with respect to the work piece W and grinding can be continued without prior testing.

If a grinding wheel of a different diameter is to be mounted on the grinding spindle, the adjusting means for the dressing device have to be disengaged from the main adjusting spindle 25 36. For this purpose, the gear 44 is moved out of engagement with the spindle 28 through loosening of the adjusting nut 47 and of the friction 30 clutch 45, 45', whereupon the dressing device is adjusted with respect to the grinding wheel S by means of the hand wheel.

The dressing device according to the invention can also be furnished with a single dressing tool 35 which shapes the grinding wheel profile to be produced by two corners and the intermediate edge of its profile. For this the stops 19 and 20 are removed and the adjustable stop screw 21 so 40 screwed against the shaft 5 that the lever 4 is immovable in the direction of its rotary axis. The use of two dressing tools is, however, preferred as in this case the disadvantages mentioned hereinbefore—shaping of the tracer—are avoided, and only a simple cylindrical tracing 45 roller is required.

The dressing device illustrated in Figures 1 to 3 may, if desired, be adapted for use with a single dressing tool. For this the stops 19 and 20 are removed and the adjustable stop screw 21 so 50 screwed against the shaft 5 that the lever 4 is immovable in the direction of its rotary axis.

All shapes of grinding wheels can be dressed with the device constructed in accordance with the invention.

55 I claim:—

1. A device for dressing profiled grinding wheels, comprising two dressing tools controlled by means of a former and of which each operates on a respective half of the grinding wheel profile, in which the dressing tools are mounted side by side on a two-armed lever adapted to turn about an axis of rotation which is in a plane parallel to the axis of the grinding wheel and also about an axis perpendicular to the plane of 60 the grinding wheel profile, the turning movements of the lever being effected by a tracer guided over a former, the tracing arm causing its guide member and a rotary shaft connected therewith to rotate together with the lever and 65 dressing tools and at the same time operates, through the intermediary of suitable members, for example a toothed rack and toothed wheel, a cam which acts on the lever in such a manner 70 as to cause the dressing tools to move radially 75 with respect to the grinding wheel.

2. A device as claimed in claim 1, in which the double lever carrying the dressing tools is arranged, with the cam controlling its movement to and from the grinding wheel, in the rotary shaft of the guide member for the tracing arm. 5

3. A device as claimed in claim 1, in which the double lever is movable in the direction of its rotary axis in order that when one half of the profile has been dressed the one dressing tool may be brought out of engagement with the 10 grinding wheel and the other brought into operative position.

4. A device for dressing profiled grinding wheels comprising a support, a former pattern mounted thereon, a grinding wheel spindle mounted to revolve on a fixed axis, a shaft mounted in said support to rotate on an axis perpendicular to the periphery of a grinding wheel on said spindle, a lever pivoted intermediate its ends to said shaft to swing about an axis perpendicular to the shaft, grinding wheel dressing means carried by one end of said lever to engage the periphery of a grinding wheel mounted on said spindle, and guide means for rotating said shaft on its axis and swinging said lever and including means to engage the former pattern. 15 20 25

5. A device for dressing profiled grinding wheels comprising a support, a former pattern mounted thereon, a grinding wheel spindle mounted to revolve on a fixed axis, a shaft mounted in said support to rotate on an axis perpendicular to the periphery of a grinding wheel on said spindle, a lever pivoted intermediate its ends to said shaft to swing about an axis perpendicular to the shaft, grinding wheel dressing means carried by one end 30 35 of said lever to engage the periphery of a grinding wheel mounted on said spindle, a head on said shaft, a guide bar slidably mounted in said head to reciprocate transversely of the shaft and having means on its outer end to engage the former pattern, and means connecting the bar and lever to oscillate the lever as the bar is protracted and retracted. 40

6. A device for dressing profiled grinding wheels comprising a support, a former pattern mounted 45 thereon, a grinding wheel spindle mounted to revolve on a fixed axis, a shaft mounted in said support to rotate on an axis perpendicular to the periphery of a grinding wheel on said spindle, a lever pivoted intermediate its ends to said shaft 50 to swing about an axis perpendicular to the shaft, grinding wheel dressing means carried by one end of said lever to engage the periphery of a grinding wheel mounted on said spindle, a head on said shaft, a guide bar slidably mounted in 55 said head to reciprocate transversely of the shaft and having means on its outer end to engage the former pattern, means connecting the bar and lever to oscillate the lever as the bar is protracted and retracted, stops limiting the movement of oscillation of said lever and means to adjust the position of at least one of said stops. 60

7. A device for dressing profiled grinding wheels comprising a support, a former pattern mounted thereon, a grinding wheel spindle mounted to revolve on a fixed axis, a shaft mounted in said support to rotate on an axis perpendicular to the periphery of a grinding wheel on said spindle, a lever pivoted intermediate its ends to said shaft to swing about an axis perpendicular to the shaft, grinding wheel dressing means carried by one end 65 of said lever to engage the periphery of a grinding wheel mounted on said spindle, a head on said shaft, a guide bar slidably mounted in said head to reciprocate transversely of the shaft and hav- 70 75

ing means on its outer end to engage the former pattern, means connecting the bar and lever to oscillate the lever as the bar is protracted and retracted, stops limiting the movement of oscillation of said lever, means to adjust the position of at least one of said stops, and a spring holding said lever against the adjustable stop.

8. A device for dressing profiled grinding wheels comprising a support, a former pattern mounted thereon, a grinding wheel spindle mounted to revolve on a fixed axis, a shaft mounted in said support to rotate on an axis perpendicular to the periphery of a grinding wheel on said spindle, a lever pivoted intermediate its ends to said shaft to swing about an axis perpendicular to the shaft, grinding wheel dressing means carried by one end of said lever to engage the periphery of a grinding wheel mounted on said spindle, guide means for rotating said shaft on its axis and swinging said lever and including means to engage the former pattern, a base whereon said support is slidably mounted to move toward and from the axis of said spindle.

9. A device for dressing profiled grinding wheels comprising a support, a former pattern mounted thereon, a grinding wheel spindle mounted to revolve on a fixed axis, a shaft mounted in said support to rotate on an axis perpendicular to the periphery of a grinding wheel on said spindle, a lever pivoted intermediate its ends to said shaft to swing about an axis perpendicular to the shaft, grinding wheel dressing means carried by one end of said lever to engage the periphery of a grinding wheel mounted on said spindle, a head on said shaft, a guide bar slidably mounted in said head to reciprocate transversely of the shaft and having means on its outer end to engage the former pattern, means connecting the bar and lever to oscillate the lever as the bar is protracted and retracted, a base whereon said support is slidably mounted to move toward and from the axis of the said spindle, and means to move the support and the parts carried thereby toward and from said spindle.

10. A device for dressing profiled grinding wheels comprising a support, a former pattern

mounted thereon, a grinding wheel spindle mounted to revolve on a fixed axis, a shaft mounted in said support to rotate on an axis perpendicular to the periphery of a grinding wheel on said spindle, a lever pivoted intermediate its ends to said shaft to swing about an axis perpendicular to the shaft, grinding wheel dressing means carried by one end of said lever to engage the periphery of a grinding wheel mounted on said spindle, a head on said shaft, a guide bar slidably mounted in said head to reciprocate transversely of the shaft and having means on its outer end to engage the former pattern, means connecting the bar and lever to oscillate the lever as the bar is protracted and retracted, stops limiting the movement of oscillation of said lever, means to adjust the position of at least one of said stops, a base whereon said support is slidably mounted to move toward and from the axis of said spindle, and means to move the support and the parts carried thereby toward and from said spindle.

11. A device for dressing profiled grinding wheels comprising a support, a former pattern mounted thereon, a grinding wheel spindle mounted to revolve on a fixed axis, a shaft mounted in said support to rotate on an axis perpendicular to the periphery of a grinding wheel on said spindle, a lever pivoted intermediate its ends to said shaft to swing about an axis perpendicular to the shaft, grinding wheel dressing means carried by one end of said lever to engage the periphery of a grinding wheel mounted on said spindle, a head on said shaft, a guide bar slidably mounted in said head to reciprocate transversely of the shaft and having means on its outer end to engage the former pattern, means connecting the bar and lever to oscillate the lever as the bar is protracted and retracted, stops limiting the movement of oscillation of said lever, means to adjust the position of at least one of said stops, a spring holding said lever against the adjustable stop, a base whereon said support is slidably mounted to move toward and from the axis of said spindle, and means to move the support and the parts carried thereby toward and from said spindle.

HERMANN GODZIEWSKI.
